UNITED STATES PATENT OFFICE.

ENOCH OSGOOD, OF BOSTON, MASSACHUSETTS.

IMPROVEMENT IN PROCESSES OF RENDERING LEATHER, FIBROUS AND POROUS MATERIALS IMPERVIOUS TO GAS.

Specification forming part of Letters Patent No. **129,901**, dated July 30, 1872.

Be it known that I, ENOCH OSGOOD, of Boston, county of Suffolk and State of Massachusetts, have invented a new and Improved Process of Rendering Leather, Fibrous and Porous Materials Impervious to Gas, preventing all gases from penetrating or escaping from such materials when made into bags, tubes, or other forms.

My invention relates to the use of glycerine for this purpose, and I carry out my invention as follows: The substances to be rendered impervious are first wrought into the desired form. When the articles are dry they are saturated with glycerine by immersion therein or by any process suitable therefor. This treatment renders them impervious to gas, preventing either its escape therefrom or penetration therewith.

If at any time any portion of the article

should become injured or pervious to gas, by reason of absorption of the glycerine by bodies with which it has come in contact, the injured part may be repaired and rendered gas-proof by recharging such parts with glycerine, or the whole article may be so treated.

Having thus described my invention, what I claim, and desire to secure by Letters Patent, is—

The herein-described process of rendering leather, fibrous and porous substances impervious to gas, preventing the penetration into or escape of gas therefrom, by the application thereto of glycerine, substantially as set forth.

ENOCH OSGOOD.
